UNITED STATES PATENT OFFICE.

ARTHUR J. RAY, OF CUBA, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ELAPSED-TIME AND ZONE METERING.

Original application filed January 22, 1923, Serial No. 614,093. Divided and this application filed April 9, 1926, Serial No. 100,810. Renewed July 11, 1928.

The present invention relates to elapsed time and zone metering in general, but is, which are denoted by dotted rectangles, are concerned more particularly with elapsed time and zone metering telephone systems in which calls are extended through the medium as representing any of the well known devices of automatic switches; and the principal object, briefly stated, is the provision of new and improved circuit arrangements whereby a calling subscriber may be charged for a completed call according to the actual location of the office or exchange in which the called line terminates, the charge being assessed at intervals during the conversation.

Another object is to accomplish the purposes above set forth by means of apparatus and circuit arrangements which are located wholly in the office in which the call originates.

Other objects have to do with the refinement of the various circuits peculiar to a system of this sort to make them more efficient and practical.

These objects, together with others which will not specifically be pointed out now, will be more fully listed hereinafter, reference being had to the accompanying drawings comprising Figs. 1 to 4, inclusive, which show by means of the usual circuit diagrams, sufficient of the apparatus employed in a system embodying the principles of the invention to enable one familiar with the art to understand the same.

This is a division of prior application, which issued as Patent No. 1,633,678, June 28, 1927.

The drawings, Figs. 1 and 2, when placed in order with corresponding lines in alignment, represent the invention when used in connection with meters located at the central office.

Figures 3 and 4, when placed in order with corresponding lines in alignment, represent the invention when used in connection with meters located at the substations.

Referring to Figs. 1 and 2, the automatic substations A, A', and A'' are ordinary automatic substations having the usual talking, signaling, and impulse sending instrumentalities.

The line switch C, Fig. 1, is mechanically of the well-known rotary type in which the wipers have no normal position and move in a forward direction only. Means are provided whereby the meter M may be associated with the metering conductor of a selected

55 whereby the closure of a circuit through a magnet results in the operation of a recording means. The meters M' and M'', Fig. 2, which are denoted by dotted rectangles, are assumed to be similar to the switch C.

The meter M, Fig. 1, may be considered as representing any of the well known devices of automatic switches; and the principal object, briefly stated, is the provision of new and improved circuit arrangements whereby the closure of a circuit through a magnet results in the operation of a recording means. The meters M' and M'', Fig. 2, which are denoted by dotted rectangles, are assumed to be similar to the meter M.

The trunk relay D, Fig. 1, comprises an electropolarized relay, having one winding which is in series with the negative side of the trunk. A reversal of the polarity of the trunk conductors will result in the energization of this relay, which, when once energized, will remain in operated position by virtue of the second winding, even though the first winding becomes deenergized. The operation of this relay serves to extend a conductor from the meter of the calling subscriber to the meter conductor of the associated first selector.

The selector E, Fig. 1, is mechanically of the well known vertical and rotary type in which the bank contacts are arranged in horizontal rows or levels. Means are provided whereby the metering conductor may be extended to a metering wiper, which is indicated by reference numerals 49 shown at the right of Fig. 1, which figure also shows the first four contacts in the second level of the bank to which this wiper has access. Certain levels in the bank of the selector E are associated with trunks leading to local second

selectors, such as the selector E'', Fig. 2. On all such levels the ten bank contacts seizable by wiper 49 are multiplied together and connected to an interrupter, such as is indicated by reference character I. As will be more fully explained hereinafter, the interrupter I may serve to energize the meter M at predetermined intervals throughout the period of conversation. Certain levels in the banks of the selector E are associated with trunks leading to repeaters, such as the repeater R, Fig. 2. On all such levels the bank contacts seizable by wiper 49 are connected to the associated repeater in the same manner as are the corresponding contacts seizable by the other wipers of selector E.

The selector switches denoted by the dotted rectangles E' and E'', Fig. 2, are each assumed to be similar to selector E, with the exception

that they are not provided with a metering wiper and the associated bank.

The automatic repeater R, Fig. 2, is an ordinary repeater of the type commonly in use, and has associated with it the switch S, which may be considered as a simple ten-point step by step switch. The switch S is provided with an operating magnet, and with a set of off normal springs which are operated when the switch wipers are advanced out of their normal position. The association between the repeater R and the switch S is such that the first digit dialled through the repeater will cause the switch S to advance its wipers a corresponding number of steps. A further operation of the repeater will not effect the switch S. The metering conductor from the bank of selector E terminates in the wiper of switch S. Certain contacts in the bank to which this wiper has access are connected to interrupters of varying frequency, such as the interrupters I' and I². As will be more fully explained hereinafter, the interrupter I' or I² may serve to energize the meter M at predetermined intervals throughout the period of conversation.

The interrupters I, I', and I² may be considered to comprise a continuously driven cam arrangement adapted to supply grounded im-

pulses at the desired frequency. The connector switches denoted by the dotted rectangles H and H', Fig. 2, are assumed to be connectors of the well known vertical and rotary type having bank contacts arranged in horizontal rows or levels.

From the foregoing, it will be seen that provision has been made to operate a meter associated with the calling line at the central station at predetermined intervals during the time of conversation, the frequency of operation being determined by the actual location of the office or exchange in which the called line terminates.

Referring to Figs. 3 and 4, A³ and A⁴ are ordinary automatic substations having the usual talking, signaling, and impulse sending instrumentalities. Associated with each substation, and adjacent thereto, is a meter denoted by the rectangles T and T', which may be considered as a device whereby the reversal of the polarity of the line conductors results in the operation of a recording means. A device of this kind is illustrated in United States Letters Patent No. 912,268, issued to Charles M. Beattie, under date of February 9, 1909.

The line switches C³ and C⁴ are similar to line switch C, Fig. 1, with the exception that no metering conductor is provided.

The selectors E⁴ and E⁵ may be assumed to be similar to selector E², Fig. 2.

The repeater R' and the switch S' are mechanically the same as repeater R and the switch S, Fig. 2, the circuits having been

modified, however, in order that a meter at 65 the substation may be operated thereby.

The connector H² is a vertical and rotary switch of the Strowger type, and is similar to connectors H and H', except that the battery feed connections for the calling line 70 are modified in order to provide for operating a meter at the substation.

The apparatus represented by the rectangles P', P², and P³ may be considered to be continuously operating devices by means of 75 which the polarity of the two associated conductors is reversed at predetermined intervals. As will be more fully explained said conductors, under certain conditions, serve as a source of battery feed for the calling line 80 and, in order that there may be no interruption of the undulatory voice currents which may be traversing said line, the apparatus is arranged to gradually decrease the potential and subsequently increase it gradually to the 85 maximum voltage. A device of this kind is shown in United States Letters Patent No. 912,268, issued to Charles M. Beattie under date of February 9, 1909.

From the foregoing it will be seen that provision has been made to operate a meter at 90 the calling substation at predetermined intervals during the conversation, the frequency of operation being determined by the actual location of the office or exchange in which the 95 called line terminates.

The system having been described in general, a detailed description will now be given of its operation. The operation of a central office meter, as the result of the establishment 100 of a local connection, will now be explained, and for this purpose it will be assumed that the subscriber at substation A, Fig. 1, desires to call the subscriber at substation A', Fig. 2, whose number is assumed to be 2536.

When the receiver is removed at the calling substation, a circuit is closed over the line conductors 11 and 12 for the line relay 13 of the line switch C. Line relay 13, upon energizing, closes at armature 14 a circuit for 110 switching relay 15 and stepping magnet 16 in series, and at armature 17 connects the test wiper 20 to a point in the circuit between the switching relay 15 and the stepping magnet 16. From this point the operation depends 115 upon whether the trunk line upon which the wipers of the line switch are standing is busy or idle. If it is busy, there is a ground potential on the test contact 23, switching relay 15 is short circuited, and the stepping magnet 16 which interrupts its own circuits is operated in the manner of a buzzer to advance the switch wipers step by step in search of an idle trunk line. In the present case, however, we shall assume that the trunk 120 line upon which the wipers of the line switch are standing is idle. This being the case, switching relay 15 is not short circuited and

stepping magnet 16 is not energized on account of the high resistance of switching relay 15. Switching relay 15, however, is energized and at armature 29 disconnects the 5 test wiper 20 from the point between its own winding and that of stepping magnet 16 and connects it to the grounded private normal conductor 30. As a further result of the energization of switching relay 15, it disconnects the line conductors 11 and 12 from the 10 winding of line relay 13 and ground, respectively, and extends them by way of armatures 31 and 32 and their working contacts, wipers 18 and 21, bank contacts 9 and 24, 15 trunk conductors 25 and 28, the upper winding of relay 43 in parallel with the non-inductive resistance 44, armatures 33 and 34 and their resting contacts to the upper and lower windings of the line relay 35 of the selector E. 20 Line relay 35 now energizes over the calling subscriber's loop and at its armature 36 closes a circuit for the slow acting release relay 37. Release relay 37 upon energizing, opens a point in the circuit of release magnet 38, prepares a circuit for relay 39 at armature 40, 25 and at armature 41 places ground upon release trunk conductor 42, thereby establishing a holding circuit for the line switch C. By means of this ground potential on test 30 contact 23 and its multiples in the banks of the other line switches which have access to the selector E, the seized trunk line is maintained busy in the usual manner. A branch of this holding circuit extends by way of private normal conductor 30 to multiple test contacts in the banks of connector switches having access to the calling line, thereby guarding it against intrusion in the usual manner. 35 The lower winding of trunk relay 43 is connected from battery to the grounded release trunk conductor 42. This relay does not operate at this time, however, because the polarity of the trunk conductors 66 and 28 is such that the two windings oppose each other. It may be mentioned that a further result of 40 the energization of the switching relay 15 was the extension of the metering conductor by way of armature 45, wiper 19, bank contact 22 to conductor 26. 45 The calling subscriber now operates his calling device in accordance with the first digit 2 of the desired number, thereby producing two interruptions in the circuit of the line relay 35 of the first selector E. As soon 50 as line relay 35 deenergizes in response to the first of these interruptions, a circuit is closed which is traceable from ground at armature 46, armature 36 and its resting contact, armature 40 and its working contact, winding of 55 the series relay 39, winding of the vertical magnet 47 to battery. Vertical magnet 47, upon energizing, raises the wipers 48 to 51, inclusive, opposite the first level of bank contacts, whereupon the off normal springs 52 close and complete a circuit traceable from 60 the grounded release trunk conductor 42 by way of armature 57 and its working contact, off normal springs 52, armature 58 and its resting contact, winding of relay 53 to battery. Stepping relay 53, upon energizing, 65 closes a point in the circuit of rotary magnet 54 at armature 55, and at armature 56 closes a locking circuit for itself independent of relay 39. When line relay 35 deenergizes in response to the second interruption produced in its circuit, the vertical magnet is again operated to raise the wipers one step, bringing them opposite the desired level of bank contacts. The relay 39, being slow acting, will remain energized while impulses 70 are passing through it to the vertical magnet. Shortly after the last vertical impulse, relay 39 will deenergize and close a circuit through the rotary magnet 54 at armature 57. Rotary magnet 54, upon energizing, advances 75 the wipers 48 to 51, inclusive, into engagement with the first set of contacts in the second level, and at armature 58 opens the circuit of stepping relay 53. Stepping relay 53, upon deenergizing, opens another point in its circuit, and at armature 55 opens the circuit of rotary magnet 54. Rotary magnet 54, upon deenergizing, again closes the contact at armature 58. 80 From this point the operation depends upon whether the trunk line terminating in the first set of contacts is busy or idle, if it is busy, the stepping relay 53 energizes again over the following circuit: from ground by way of the test contact with which test wiper 50 is in engagement, test wiper 50, armature 61 and its resting contact, off normal springs 52, armature 58 and its resting contact, winding of relay 53 to battery. Stepping relay 53, upon energizing, 85 closes a locking circuit for itself at armature 56 and at armature 55 again completes the circuit of rotary magnet 54. This alternate operation of the stepping relay and rotary magnet continues so long as test wiper 50 engages grounded contacts. In 90 this case we will assume that the trunk line comprising conductors 108 to 111, inclusive, is the one first found to be idle. That being the case, when the wipers of the selector E arrive upon the bank contacts 62 to 65, inclusive, there is no ground potential on test contact 64 and, consequently, stepping relay 53 does not energize. With this condition existing, switching relay 59 energizes 95 over the following circuits: from ground by way of release trunk conductor 42, switching relay 59, off normal springs 52, armature 58 and its resting contact, winding of relay 53 to battery. Stepping relay 53, however, does not energize over this circuit on account of 100 the relatively high resistance of switching relay 59. Switching relay 59, upon energizing, removes ground from armature 40 of release relay 37 at armature 46; disconnects test wiper 50 from the point between switch- 105

ing relay 59 and stepping magnet 53 and connects it to ground by way of release trunk conductor 42 at armature 61, thus making the seized trunk busy immediately; and at armatures 33 and 34 disconnects the line conductors 66 and 28 from the windings of line relay 35 and extends them by way of the working contacts of these armatures, wipers 48 and 51, bank contacts 62 and 65, trunk conductors 108 and 111 to the line relay of the incoming second selector E², Fig. 2. Selector E² thereupon places ground upon the release trunk conductor 110, thereby establishing the usual holding circuit for the selector E and the line switch C before the slow acting release relay 37 of selector E has had time to deenergize. A further result of the energization of relay 59 is the extension of metering conductor 67 by way of armature 68, wiper 49, bank contact 63, and conductor 109 to interrupter I.

The calling subscriber dials now the second digit 5 of the called number. Responsive to this action, the selector E² raises its wipers to the fifth level and selects an idle trunk line extending to a connector switch, which we will assume is the connector H. When the calling subscriber dials the third digit 3 of the called number, the connector H will raise its wipers to the third level of the bank contacts. The calling subscriber now dials the final digit 6 of the called number; as a result of which the connector rotates its wipers six steps to position them upon the terminals of the line extending to the station A'. Upon the completion of the connection, a signaling circuit is established in the connector in the usual manner, and the bell at the called station is operated to notify the subscriber that he is wanted.

When the called party answers, the connector will cause a reversal of the polarity of the trunk conductors in the usual well known manner. The trunk relay 43, Fig. 1, will now operate, as the polarity of the trunk conductors is such that the current in its two windings assist each other. When once energized, the lower winding of relay 43 will hold said relay in operated position irrespective of the deenergization of its upper winding. Relay 43, upon energizing, connects metering conductor 26 with metering conductor 67 by way of armature 69, at the same time short circuiting its upper winding and the non-inductive resistance 44, at armature 70. The meter M will now be operated at predetermined intervals by the interrupter I until the connection is released. The circuit over which the meter is operated is traceable from ground at the interrupter I, by way of bank contact 63, metering wiper 49, armature 68, conductor 67, armature 69, conductor 26, bank contact 22, metering wiper 19, armature 45, winding of meter M to battery. The release of the connection is controlled by the calling subscriber, who, when the conversation is completed, will replace the receiver; as a result of which the line and release relays of the connector H will deenergize and remove ground from the release trunk conductor. It follows that all of the automatic switches involved in the connection are restored to normal according to well known practice.

The operation of a central office meter as the result of the establishment of an inter-office connection will now be explained. For this purpose it will be assumed that the subscriber at substation A, Fig. 1, desires to call the subscriber at substation A', Fig. 2, whose number is assumed to be 1536. When the calling subscriber removes his receiver, his line is extended to a first selector as previously explained, and it shall be assumed that selector E is the one taken for use. The selector E now responds to the dialling of the first figure 1 of the called number, and operates to raise its wipers to the first level to select an idle trunk line extending to a repeater, which we will assume to be the repeater R, Fig. 2. Switching relay 59 of the selector E, upon operating disconnects the line conductors 66 and 28 from the windings of line relay 35, and extends them by way of the working contacts of armatures 33 and 34, wipers 48 and 51, bank contacts 70 and 73, trunk conductors 112 and 114, and the normally closed contacts controlled by armatures 117 and 118 to the upper and lower windings of the line relay 119 of the repeater R. Line relay 119 now energizes over the calling subscriber's loop and at armature 120 closes the circuit of release relay 121. Release relay 121, upon energizing, prepares a circuit for relay 122 at armature 123 and places ground on release trunk conductor 113 at armature 124, thereby establishing the usual holding circuit for the selector E and the line switch C before the slow acting release relay 39 of selector E has had time to deenergize. A further result of the energization of relay 59 is the extension of metering conductor 67 by way of armature 68, wiper 49, bank contact 71, conductor 115 to wiper 134 of switch S.

Referring to the repeater R, as a further result of the energization of release relay 121, a circuit is closed through the lower winding of the electro-polarized relay 125 at armature 126. This winding alone, however, consisting of a few turns of high resistance is not able to effectively operate the relay. As a still further result of the energization of release relay 121, it completes at armature 128 a bridge across the trunk conductors 129 and 130 as follows: from conductor 129 by way of armature 128 and its working contact, armature 131 and its resting contact, upper winding of electro-polarized relay 125, impedance 132, working contact and armature 133 to conductor 130. In response to the closure of this bridge, the line and release

relays of the second selector E^3 in the distant office energize and prepare the switch for operation in the usual manner. Electro-polarized relay 125, however, is not energized at this time owing to the fact that the current flowing in either winding is in a direction opposite to that flowing in the other winding.

The calling subscriber now operates his calling device in accordance with the second figure 5 of the desired number, thereby producing a corresponding number of interruptions in the circuit of line relay 119. Each time line relay 119 deenergizes, it opens the circuit of the line relay of the incoming second selector E^3 at armature 133, and at armature 120 closes a circuit traceable from ground at armature 120 and its resting contact, armature 123 and its working contact, conductor 135, winding of relay 122 to battery. A branch of the above traced circuit may be traced from grounded conductor 135, armature 136 and its resting contact, winding of the stepping magnet 137 of the switch S to battery. At armature 131 relay 122 completes the bridge across trunk conductors 129 and 150 over a more direct path excluding the upper winding of relay 125 and the impedance 132. This is the usual expedient made use of to obtain improved switch control.

The stepping magnet 137 of the switch S , in response to the five impulses of current sent through it by the line relay 119, operates to advance the wiper 134 into engagement with the fifth contact in the associated bank, and the interrupter I' is now connected to the metering conductor 67, Fig. 1. The relay 122, being slow acting, maintains its armature in operated position so long as impulses are passing through it. Shortly after the completion of the first series of impulses, the relay 122 deenergizes and closes a circuit traceable from ground at armature 138, by way of off normal springs 139, which are closed at the first step of the magnet 137, winding of cutoff relay 140 to battery. The cutoff relay, upon energizing, opens the circuit of the stepping magnet 137 at armature 136, in order to prevent further operation of stepping magnet 137 by the line relay 119. Furthermore, relay 140, upon energizing, closes a locking circuit for itself at armature 141, thus rendering it independent of the further operation of relay 122.

The incoming second selector E^3 , in response to the five interruptions produced in the circuit of its line relay, raises its wipers to the fifth level of bank contacts and selects an idle trunk line leading to a connector, which we will assume to be the connector H' . When the calling subscriber dials the third figure 3 of the called number, a series of three impulses are produced which are repeated by the repeater R to the connector H' , which raises its wipers to the fifth level of bank con-

tacts. When the calling subscriber dials the final figure 6 of the called number, a series of six impulses are produced which are repeated by the repeater R to the connector H' , which is operated in the usual manner to 70 rotate its wipers into connection with the line extending to the substation A^2 . Upon the completion of the connection to the called line, a signaling circuit is established in the connector in the usual manner and the bell 75 at the called station is operated to notify the subscriber that he is wanted.

When the called party answers, the connector will cause a reversal of the polarity of the trunk conductors 129 and 130 in the usual 80 well known manner. Returning to a consideration of the repeater R , it may be said that the polarized relay 125 will now operate, as the polarity of the trunk conductors is such that the current in its two windings assist each other. When once energized, the lower winding of relay 125 will hold said relay in an operated position irrespective of the direction of the current flow in its upper winding. Relay 125, upon energizing, causes 85 a reversal of the polarity of the trunk conductors 112 and 114, and as a result, the electro-polarized relay 43, Fig. 1, will now operate, as the polarity of the trunk conductors is such that the current in its two windings assist 90 each other. When once energized, the lower winding of relay 43 will hold said relay in an operated position irrespective of the deenergization of its upper winding. Relay 43, upon energizing, connects metering conductor 26 with metering conductor 67 by way 95 of armature 69, at the same time short circuiting its upper winding, and the non-inductive resistance 44, at armature 70. The meter M will now be operated at predetermined intervals by the interrupter I' until such time as the connection is released. The circuit over which the meter is operated is traceable from ground at interrupter I' , wiper 134 in fifth position, conductor 115, 100 bank contact 71, wiper 49, armature 68, conductor 67, armature 69, bank contact 22, wiper 19, armature 45, winding of meter M to battery. The release of the connection is controlled by the calling subscriber, who, 105 when the conversation is completed, will replace his receiver, thereby causing the deenergization of the line and release relays 119 and 121 of the repeater R . As a result of the foregoing, the holding circuit for the 110 automatic switches in the originating exchange is broken, with the further result that the control circuit extending over the trunk conductors 129 and 130 is broken also. It follows that all of the automatic switches involved in the connection are restored to normal according to well known practice. The release of the switch S is brought about by the deenergization of release relay 121 of the repeater R , a circuit being closed from ground 115

120

125

130

at armature 126 and its resting contact, by way of armature 142 and its working contact, winding of release magnet 143 to battery. Release magnet 143, upon energizing, causes the release of switch S, the wiper 134 restoring to its normal position. The restoration of wiper 134 to its normal position causes the off normal springs 139 to be opened, and as a result relay 140 will deenergize and open the circuit of the release magnet 143 at armature 142, thus completing the releasing operation.

If the repeater R is used only in extending calls to a single distant office, it follows that the first figure dialled on the repeater will always be the same. Under the condition stated above, it would not be advisable to combine a switch, such as the switch S, with the repeater, for the same metering could be obtained by connecting the interrupter I' to the bank in the level associated with the group of repeaters of which repeater R forms a part. It is advisable to use the switch S in connection with a repeater, such as the repeater R, only when the repeater is used to extend connections to two or more distant offices. In further explanation, we may assume that the contacts in the sixth level of the incoming second selector E³, Fig. 2, are associated with the trunk lines leading by way of repeaters to incoming third selectors in a distant office. The first two digits in the call number of a telephone located in the last mentioned office are necessarily 16. When calling a number located therein, the dialling of the second digit 6 will operate the line relay 119 of the repeater R six times, which results in the advancement of the wiper 134 into engagement with the sixth contact in its bank and at the same time causes the incoming second selector E³ to raise its wipers opposite the sixth level of bank contacts; following which it selects an idle trunk line extending to a repeater, which trunk line may be assumed to comprise the conductors 144, 145, and 146. The advancement of the wiper 134 has resulted in the connection of the interrupter I² to the metering conductor 67, Fig. 1, and, when the connection is completed and the called party has answered, the polarized relay 43, Fig. 1, will operate in the usual manner to connect the interrupter I² with the meter M. The meter M will then be operated at predetermined intervals by the interrupter I² until the connection is released. The release of the connection is controlled by the calling subscriber in the usual manner.

The operation of a substation meter, as the result of the establishment of an inter-office connection, will now be explained. For this purpose it will be assumed that the subscriber at substation A³, Fig. 3, desires to call the subscriber at substation A⁴, Fig. 4, whose number is assumed to be 3236. When

the calling subscriber removes his receiver, no operation of the meter T takes place, as the normal line polarity is such that the meter is inoperative at this time. The line, however, will be extended to a first selector 70 in the usual manner, it being assumed that the selector E⁴ now responds to the dialling of the first figure 3 of the called number, and operates to raise its wipers to the third level and selects an idle trunk line extending 75 to a repeater, which we will assume to be the repeater R'. The extension may be traced from trunk conductors 210 and 211, the upper and lower windings of line relay 212, armatures 213 and 214 and their resting 80 contacts, resistances 215 and 216, to battery and ground, respectively. The line relay 212 energizes over the calling subscriber's loop and at armature 217 closes the circuit of release relay 218, which relay, upon energizing, places ground upon release trunk conductor 219, thereby establishing the usual holding circuit for the selector E⁴ and the line switch C³.

The calling subscriber now operates his 90 calling device in accordance with the second digit 2 of the called number, as a result of which the repeater R' operates in a manner similar to that previously described in connection with repeater R, Fig. 2, to advance the wipers 220 and 221 of the switch S' into engagement with the second contact in their respective banks; at the same time causing the incoming second selector E⁵ to raise its wipers opposite the second level of bank contacts. The selector E⁵ thereupon selects an idle trunk line extending to a connector, which we will assume to be the connector H². The extension may be traced from trunk conductor 322 and 323, the upper 100 and lower windings of line relay 324, armatures 325 and 326 and their resting contacts, resistances 327 and 328, to battery and ground, respectively. The line relay 324 now energizes over the trunk loop from repeater R' and at armature 329 closes the circuit of release relay 330, which relay, upon energizing, places ground upon the release trunk conductor 331, thereby establishing the usual 105 holding circuit for the selector E⁵.

The calling subscriber now operates his calling device in accordance with the third figure 3 of the called number, and a series of three impulses are produced which are repeated by the repeater R' to the connector H², which raises its wipers to the third level of bank contacts. When the calling subscriber dials the final figure 6 of the called number, a series of six impulses are produced which are repeated by the repeater R' to the connector H², which is operated in the usual manner to rotate its wipers into connection with the line extending to the substation A⁴. Upon the completion of the connection to the called line, a signaling circuit is estab- 115 120 125 130

lished in the connector in the usual manner, and the bell at the called substation is operated to notify the subscriber that he is wanted.

5 When the called party answers, he will draw talking battery through the back bridge relay 332, which, upon energizing, closes a circuit for relay 333 at armature 341. Relay 333, upon energizing, forms a locking circuit 10 for itself from the grounded release trunk conductor 331 by way of armature 334. A further result of the operation of relay 333 is the substitution at armatures 325 and 326 of the pole changer P^3 for the normal battery 15 feed represented by the resistances 327 and 328. The pole changer P^3 now feeds current to the trunk conductors 322 and 323 by way of armatures 325 and 326 and the upper and lower windings of line relay 324, the polarity 20 changing at predetermined intervals dependent upon the structure of the pole changer.

Sometime subsequent to the operation of relay 333, the polarity of the trunk conductors will be such that the polarized relay 235 25 of the repeater R' , Fig. 2, will become operated, and, it is to be remembered, when this winding is once operated, the lower winding is effective to hold the said relay in an operated position irrespective of the direction of 30 the current flow in its upper winding. Relay 235, upon operating, substitutes the pole changer P^2 for the resistances 215 and 216, at armatures 213 and 214. The pole changer P^2 now feeds current to the calling line by 35 way of wipers 220 and 221, armatures 213 and 214, upper and lower winding of line relay 212 and trunk conductors 210 and 211, the polarity changing at predetermined intervals dependent upon the structure of the 40 pole changer. The meter T at the substation A^3 will now operate in response to the changes 45 of polarity until such time as the connection is released. The release of the connection is controlled by the calling subscriber, who, 50 when the conversation is completed, will replace his receiver, thereby causing the deenergization of the line and release relays 212 and 218 of the repeater R' . As a result of the foregoing, the holding circuit for the automatic 55 switches in the originating exchange is broken, with the further result that the control extending over the trunk conductors 236 and 237 is broken also. It follows that all of the 60 automatic switches involved in the connection are restored to normal according to well known practice. The release of the switch S' is brought about in a manner similar to that previously explained in connection with switch S , Fig. 2.

65 If the called station is located in the same office as the calling station, the connection will be built up without the use of a repeater, the final connection being made by a connector switch similar to connector H^2 ; in this case the meter at the calling station will be

operated directly by the pole changer associated with the said connector.

As previously explained in connection with repeater R , Fig. 2, it is advisable to associate a switch S' with the repeater R' only when 70 the repeater is used to extend a connection to two or more distant offices. In further explanation, we may assume that the contacts in the third level of the incoming second selector E^5 , Fig. 4, are associated with trunk 75 lines leading by way of repeaters to incoming third selectors in a distant office. When calling a number located therein, the dialling of the second digit 3 will operate the line relay 212 of the repeater R' three times, which results in the advancement of the wipers 220 and 221 into engagement with the third contacts in their respective banks, and at the same time causes the incoming second selector 80 E^5 to raise its wipers opposite the third level 85 of bank contacts; following which it selects an idle trunk line extending to a repeater, which trunk line may be assumed to comprise the conductors 338, 339, and 340. The advancement of the wipers 220 and 221 has prepared the circuit of pole changer P' , and, when the connection is completed and the called party has answered, the polarized relay 235 will operate in the usual manner to connect pole changer P' to the calling line. 90 The meter T will now be operated at predetermined intervals by the pole changer P' until the connection is released; the release of the connection being controlled by the calling subscriber in the usual manner. 100

The object and scope of the invention having been described, what is considered to be new and what it is desired to have protected by Letters Patent will be pointed out more specifically in the appended claims. 105

What is claimed is:

1. In a multi-office telephone system, two exchanges, elapsed time meters at the subscribers' stations connected to said exchanges, connector switches in each exchange for connecting with called lines, periodic reversing mechanism associated with said connectors for reversing the talking current supply to calling lines to control the meters at the calling stations, repeaters in each exchange arranged to cooperate with the connectors in the other exchange to establish inter-exchange connections, and periodic reversing mechanism associated with said repeaters for reversing the talking current supply to calling lines, the said mechanism associated with the repeaters operating at a different rate from the mechanism associated with the connectors. 110

2. In a multi-office telephone system, two exchanges, elapsed time meters at the subscribers' stations connected to said exchanges, connector switches in each exchange for connecting with called lines, periodic reversing mechanism associated with said connectors for reversing the talking current supply to 115 calling lines, the said mechanism associated with the repeaters operating at a different rate from the mechanism associated with the connectors. 120

calling lines to control the meters at the calling stations, repeaters in each exchange arranged to cooperate with the connectors in the other exchange to establish inter-exchange connections, and periodic reversing mechanism associated with said repeaters for reversing the talking current supply to calling lines, the said mechanism associated with the repeaters operating at a different rate from the mechanism associated with the connectors and being normally disconnected from all the repeaters, and means in each repeater responsive to the first reversal received from a connector for connecting the repeater reversing mechanism to control the meter at the calling station.

3. In a multi-office telephone system, three exchanges, elapsed time meters at the subscribers' stations connected to said exchanges, connector switches in each exchange for connecting with called lines, periodic reversing mechanism associated with said connectors for reversing the talking current supply to calling lines to control the meters at the calling stations, repeaters in the first exchange arranged to cooperate with the connectors in the other exchanges to establish inter-exchange connections, periodic reversing mechanism associated with said repeaters, there being a different mechanism for each of the other exchanges, each operating at a different rate from the other, and an auxiliary switch for each repeater controlled in accordance with the exchange to which a connection is extended to select the corresponding mechanism in order to operate the meter at the calling station.

4. In a multi-office telephone system, three exchanges, elapsed time meters at the subscribers' stations connected to said exchanges, connector switches in each exchange for connecting with called lines, periodic reversing mechanism associated with said connectors for reversing the talking current supply to calling lines to control the meters at the calling stations, repeaters in the first exchange arranged to cooperate with the connectors in the other exchanges to establish inter-exchange connections, periodic reversing mechanism associated with said repeaters, there being a different mechanism for each of the other exchanges, each operating at a different rate from the other, an auxiliary switch for each repeater controlled in accordance with the exchange to which a connection is extended to select the corresponding mechanism, and means responsive to the first reversal received from the connector in use for connecting the selected mechanism to operate the meter at the calling station.

5. In a telephone system comprising a plurality of exchanges, a calling line provided with a meter, switches including a repeater and a connector for extending local calls and interexchange calls, means associated with

said repeater for periodically reversing the current supply at said calling line to operate said meter during an inter-exchange call in accordance with a certain rate corresponding to the location of the called exchange, and means associated with said connector for periodically reversing the current supply at said calling line to operate said meter during a local call in accordance with a different rate.

6. In a telephone system comprising a plurality of exchanges, a calling line provided with a meter, switches including a repeater and a connector for extending local calls and inter-exchange calls, a plurality of mechanisms associated with said repeater, each operable to periodically reverse the current supply at said calling line at a certain rate during an inter-exchange call to operate said meter to assess a charge corresponding to the location of the called exchange, and means associated with said connector for periodically reversing the current supply at said calling line to operate said meter during a local call in accordance with a different rate.

7. In a telephone system comprising a plurality of exchanges, lines provided with meters, said lines having access to connectors for extending local calls and to repeaters for extending inter-exchange calls, a plurality of mechanisms associated with each of said repeaters and in number corresponding to the number of exchanges accessible to said repeater for periodically reversing the current supply at a calling line during an inter-exchange call to operate the meter thereat at a rate corresponding to the location of the called exchange, and a single mechanism associated with each of said connectors for periodically reversing the current supply at a calling line during a local call to operate said meter at a different rate.

8. In a telephone network comprising a plurality of exchanges, a calling line equipped with a lapse time meter, means including a subscriber controlled connector switch for completing a connection to a called line, means in said connector switch for periodically operating said meter providing the call has been initiated by a line of the exchange in which the connector is located and for simply initiating such operation if the calling line is of another exchange.

9. In a telephone system comprising a plurality of exchanges, a calling line provided with a substation meter, means for extending local and interexchange calls between said line and called lines, means for supplying talking current to said calling line, and means for causing said talking current to periodically become effective to actuate the said meter during the entire period of talking connection remains established at a rate dependent upon the location of the called line with respect to said calling line.

10. In a multi-office telephone system, two exchanges, elapsed time meters at the subscribers' stations radiating from said exchanges, automatic switches in each exchange 5 for connecting with called lines, mechanism associated with said switches for fluctuating the talking current supply to a calling substation to control its associated meter, means in each exchange arranged to cooperate with 10 the automatic switches in the other exchange to establish inter-exchange connections, and mechanism associated with said means at each exchange for causing a fluctuation of the talking current supply to the substations of the 15 calling lines, the said mechanism associated with said means in each exchange operating at a different rate than the mechanism associated with said automatic switches.
11. In a telephone system including a plurality of switching centers, calling and called lines radiating from such switching centers, means including a connector for establishing 20 a connection between two lines of the same switching center and including a repeater in 25 connections established between lines of different switching centers, a pole changing
- device associated with said connector operative to actuate a meter to charge for the connection if the same is between two lines of the same switching center and a plurality of pole 30 changing devices associated with said repeater operable to actuate a meter to charge for connections between lines of different switching centers.
12. In a telephone system comprising a plurality of exchanges, a calling line provided with a meter, means for extending local and interexchange calls between said line and called lines, means for supplying talking current to said calling line, and means for causing 35 said talking current to have its direction of flow over the calling line to be reversed to cause it to periodically become effective to actuate the said meter during the entire period the talking connection remains established at a rate dependent upon the location 40 of the called line with respect to said calling line.

In witness whereof, I hereunto subscribe my name this 22nd day of March, A. D. 1926.

ARTHUR J. RAY.
